[57] CLAIM

The ornamental design for a bag support, as shown and described.

DESCRIPTION

FIG. 1 is a perspective view of a bag support showing my new design;

FIG. 2 is a side elevational view thereof, the opposite side elevational view being a mirror image of that shown; and,

FIG. 3 is a top plan view thereof, the bottom plan view being a mirror image of that shown.

FIG. 2

FIG. 3

FIG. 1
